UNITED STATES PATENT OFFICE.

ARTHUR BRAY, OF LEEDS, ENGLAND, ASSIGNOR TO GEORGE BRAY & COMPANY,
LIMITED, OF LEEDS, ENGLAND.

GAS-BURNER.

1,281,903.

Specification of Letters Patent.

Patented Oct. 15, 1918.

Application filed August 28, 1918. Serial No. 251,811.

To all whom it may concern:

Be it known that I, ARTHUR BRAY, a subject of the King of Great Britain and Ireland, and residing at Bagby Works, Leices-
ter Place, Leeds, in the county of York, Eng-
land, have invented certain new and useful
Improvements in or Relating to Gas-Burn-
ers, of which the following is a specification.

This invention relates to gas burners for
10 lighting purposes of the luminous flat flame
type. In such burners the body is a brass
tube cylindrical along the greater part of its
length and having its lower end tapered and
screwed for fixing into the socket of the gas
15 fitting. Inside the cylindrical tube a "dimin-
isher" is inserted for the purpose of
throttling and steadyng the flow of the gas
to the burner, and also for providing that
the flow shall be uniform at the upper part
20 of the body. A steatite or other tip with
the usual orifice for the exit of the gas is
securely fixed to the upper end of the cylind-
rical brass body. The diminisher as
25 usually employed in present practice con-
sists of a small plug of pot ware pierced
with a central bore expanding toward the
top of the plug and having a paper washer
at the bottom of its outer surface and seven
30 or eight disks of muslin suitably fastened
over the top of the plug. The said disks of
muslin are held in position in the metal
socket by one or more rings of zinc or other
suitable metal. The diminisher is inserted
35 toward the bottom of the cylindrical brass
body but no part of it projects into the tapers
part thereof.

The object of the invention is to provide
a burner with improved means for securing
the desired uniformity of flow of the gas
40 through the upper part of the body, securing
greater freedom from hissing which may
be due to slight pulsations in the pressure
and velocity of the gas in the upper part of
the burner.

45 Another object of the invention is to re-
duce the manufacturing cost of the burner.

The invention consists in an improved
form of diminisher having a bore consider-
50 ably longer than its diameter giving in-
creased resistance to flow and adapted for
location mainly in the lower end of the
body.

The improved diminisher occupies less
space axially along the cylindrical body of

the burner, and requires a less axial length 55
of expansion chamber between the dimin-
isher and steatite or other tip. From these
two causes the total length of the brass body
is reduced by nearly 33 per cent. thus effect-
ing a saving in metal, and in the cost of the 60
drawing operations required to produce the
tubular body from a sheet metal blank.

I append a sectional drawing on an en-
larged scale illustrating my invention as ap-
plied in one form to English type burners 65
having an outside taper screw.

In carrying the invention into effect in
one form as applied to English type burners
having an outside taper screw, the dimin-
isher D is tapered, and fits into the taper 70
part of the burner socket, and projects above
the bottom of the tubular body of the burner.
Three or four disks of muslin M or the like
are fastened above and in contact with the
upper end of the diminisher by one ring of 75
zinc or other suitable material as above de-
scribed. (In the usual form of diminisher
with seven or eight muslin disks, it is found
that more than four disks cannot conven-
iently be fastened by one ring.) The folded 80
edges of the muslin disks fit tightly inside
the tubular body, near the lower end of the
cylindrical part thereof, thus preventing
passage of the gas except through the meshes
of the muslin. The bore of the diminisher 85
is reduced in diameter as compared with
that required hitherto and made longer, thus
increasing the throttling or steadyng action
of the diminisher. This increased resistance
of the diminisher enables a smaller number 90
of muslins and their holding rings to be
used, and consequently enables the length of
the expansion chamber between the dimin-
isher and the tip to be reduced.

Thus the invention provides an improved 95
burner with a shorter body than required
hitherto, which can be manufactured at a
lower cost.

Having now described my invention, what
I claim as new and desire to secure by Let- 100
ters Patent is:—

1. A gas burner of the type described com-
prising a tubular metal shell, a diminisher
located in the lower portion of said shell
and having a bore of considerably greater 105
length than diameter, porous material located
in the shell above the diminisher, a ring for
securing said porous material in place, and

a tip located at the upper end of the shell in close proximity to said ring.

2. A gas burner of the type described, comprising a tubular metal shell or body tapered and screwed at one end, a diminisher having its bore of considerably greater length than its diameter and fitting in the tapered part of the tubular shell, disks of muslin or the

like frictionally held above the diminisher by a single ring, and a tip of steatite or suitable material at the upper end of the tubular shell in close proximity to the said ring and muslin disks.

In testimony whereof I have signed my name to this specification.

ARTHUR BRAY.
